Primary Examiner — Paula Greene(74) *Attorney, Agent, or Firm* — Altera Law Group, LLC(57) **CLAIM**

The ornamental design for an earphone, as shown and described.

DESCRIPTION

FIG. 1 is a rear perspective view of an earphone showing my new design;

FIG. 2 is a front elevational view thereof.

FIG. 3 is a back elevation view thereof.

FIG. 4 is a left side elevational view thereof.

FIG. 5 is a right side elevational view thereof.

FIG. 6 is a top end elevational view thereof; and,

FIG. 7 is a bottom end elevational view thereof.

Portions shown in broken lines are for environmental purposes but do constitute a part of the claimed invention.

1 Claim, 6 Drawing Sheets(56)
